US0D1014080S

(12) **United States Design Patent** (10) **Patent No.:** **US D1,014,080 S**
(45) **Date of Patent:** **** Feb. 13, 2024**

(54) **SUPPRESSOR COVER**

(71) Applicant: **Brandon L. Maddox**, Sioux Falls, SD
(US)

(72) Inventor: **Brandon L. Maddox**, Sioux Falls, SD
(US)

(**) Term: **15 Years**

(21) Appl. No.: **29/701,442**

(22) Filed: **Aug. 12, 2019**

(51) **LOC (14) Cl.** **22-01**

(52) **U.S. Cl.**

USPC **D22/108**; D3/262

(58) **Field of Classification Search**

USPC D3/262; D22/108; D21/573; D29/113,
D29/120.1; D24/190

CPC F41G 1/383; F41C 27/00

Woods, Fuller, Shultz & Smith, PC

(57) **CLAIM**

The ornamental design for a suppressor cover, as shown and described.

DESCRIPTION

FIG. 1 is a perspective view of a suppressor cover showing my new design;

FIG. 2 is a top plan view of the suppressor cover;

FIG. 3 is a right side elevational view of the suppressor cover;

FIG. 4 is a left side elevational view of the suppressor cover;

FIG. 5 is a bottom plan view of the suppressor cover;

FIG. 6 is a front elevational view of the suppressor cover; and,

FIG. 7 is a rear elevational view of the suppressor cover. The broken lines illustrate conventional stitching and form no part of the claimed design.

1 Claim, 3 Drawing Sheets
